JOHN LAWSON, OF CENTRAL FALLS, RHODE ISLAND.

SPLIT-FOOT-KNITTING MACHINE.

1,166,057.

Specification of Letters Patent. Patented Dec. 28, 1915.

Application filed March 2, 1911. Serial No. 611,826.

To all whom it may concern:

Be it known that I, JOHN LAWSON, a citizen of the United States, residing at Central Falls, in the county of Providence and State 5 of Rhode Island, have invented certain new and useful Improvements in Split-Foot-Knitting Machines, of which the following is a specification.

The improvement forming the subject of 10 this application for U. S. patent relates to full automatic stocking-knitting machines for producing "split-foot" stockings. The patent to Hemphill, No. 933,443, of September 7, 1909, discloses an example of stocking-knitting machine in which the prior art of 15 knitting is embodied, and in which the applicant's improvements are capable of being successfully employed.

The object of the invention is to increase 20 the efficiency of automatic double-feed stocking-knitting machines in a simple, inexpensive and effective manner.

To that end the invention consists essentially in constructing the secondary knitting-cams whereby they may be temporarily positioned or moved outward from the face of the reciprocating cylinder to a much less extent than heretofore practised during the production of the split-foot portion of the 25 stocking, thereby at the same time correspondingly increasing the degree of engageable area of the butt portion of the long-butt needles with the thus positioned secondary knitting-cams, while the secondary 30 thread is being knitted into semi-courses of stitches. At the same time, too, the other or main thread is also being converted into semi-courses by means of the normal operative engagement of the short-butt needles 35 with the main knitting-cams; the butts of 40 these needles then moving freely and idly in the space formed between the temporarily outwardly positioned secondary knitting-cams and cylinder during each reciprocation 45 of the latter.

In the accompanying sheet of drawings, Figure 1 represents a partial top plan view of a double-feed stocking-knitting machine, showing the main and secondary knitting-cams and knitting-cylinder, the latter being indicated in horizontal section; the major portion of the operative devices being omitted. Fig. 2 is a combined transverse sectional view and end elevation, viewed from 50 the left end of the machine. Fig. 3 is a 55 partial front side elevation corresponding

with Fig. 2. Fig. 4 represents, in enlarged scale, an inner elevation of the radially movable secondary cam-block provided with stitch-cams embodying my improvement; 50 and Fig. 5 is a side elevation of one of the stitch-cams proper, embodying my improvement, viewed from the left of Fig. 4.

In a co-pending application, filed by me in the U. S. Patent Office, January 10, 1911, 65 Serial No. 601,894, is illustrated and described a double-feed knitting-machine, the same being also adapted to produce split-foot stockings, and including in its construction main and secondary knitting or stitch-cams. My present invention, as before stated, relates more particularly to improvements in the secondary knitting-cams, such 70 for example as are adapted to be moved toward and from the needle-cylinder and 75 used in knitting-machines of the double-feed type.

In the accompanying drawings a^2 designates the table of the machine, portions being omitted; the table is surmounted by a cam-plate H capable of short vertical movements. On the cam-plate are mounted the cam-block D provided with the pair of main stitch-cams x x , the radially movable cam-block D^1 carrying the pair of secondary 85 stitch-cams x^1 x^1 and the sectional needle-supporting ring-cam M^1 . The central hole or bore r of the cam-ring and table and also the inner concave faces of both sets of knitting-cams correspond to and have substantially 90 the same inner diameter as the outer diameter of the needle-carrying knitting-cylinder N , the latter being represented in horizontal section, n indicating the needles.

The secondary cam-block D^1 is mounted 95 so as to be moved bodily in a horizontal plane toward and from the cylinder N by means soon to be described. The opposite sides of the block (see Fig. 4) are beveled at an angle of about 45° and have secured thereto a pair of right and left stitch-cams x^1 x^1 ; the cam portion proper is substantially wedge-shaped, its point e being at the top end. Upper and lower vertically alining center guide members m^1 m , respectively, 105 are located with respect to the cams x^1 and secured to the inner face of the block; these form, in connection with the side cams x^1 , grooves or paths adapted, when in use, to receive the butts of the needles, substantially 110 as usual. The lower broken parallel lines $\#$ indicate the path of the butts when the

needles are in the normal working plane, and the upper broken lines t^1 the path of the butts of the long-butt needles when the latter are moved upward out of knitting 5 action.

When both the main and secondary knitting-threads are being simultaneously knitted into continuous circular courses of stitches, as in plain double-feed knitting, 10 the secondary cam-block D^1 is in the inward position, all the needles of the cylinder then being in the normal or lower plane; so that the rotation of the cylinder causes the butts to successively engage the outer inclined 15 face n^1 of one of the cams, say the right stitch-cam of the auxiliary cam-block, see Fig. 4, thereby guiding the needles upward until their respective butts engage the adjacent inclined side of the upper guide member 20 m^1 , located intermediate the said upper and lower parallel needle-paths t^1 , t , respectively; the resulting co-action successively deflects the needles back into the lower path t until they engage the lower inclined side of 25 the left stitch-cam, which latter in turn deflects the butts downward past the heel of the cam to successively cast off the loops from the needles in producing the stitches, followed by moving the needles upward to 30 the lower or knitting plane again.

In Fig. 1 the secondary cam-block D^1 is shown in the outwardly or laterally moved mid-position with respect to the knitting cylinder. In the represented position of the 35 main and secondary cams the machine is adapted to produce the split-foot portion of the stocking from the corresponding knitting-threads, the cylinder being actuated in a rotary-reciprocatory manner. The position 40 of the cam-controlling means shown in Figs. 2 and 3 corresponds with the position of the cam-block D^1 represented in Fig. 1.

The upper portion of the inner or vertical face o of each of the stitch-cams x^1 is cut 45 away to form a lateral recess or notch n^2 , the lower edge of the latter being in substantial horizontal alinement with the lower portion of the said normal butt-path t and the upper end of the lower guide member m . The depth of said recessed portion is about 50 one-half the width of the inclined surface n^1 , as clearly shown in Fig. 5. As thus devised, the butts of all the needles will, even then, in moving along the surface n^1 , extend 55 sufficiently beyond the recess, when the block D^1 is inward against the cylinder, to be normally acted upon by the stitch-cams and guide members. When, however, the secondary thread is to be inactive, as during 60 the knitting of the heel and toe pockets, the block D^1 is moved outward the maximum distance so that the butts of the short-butt needles of the then reciprocating cylinder will travel freely and idly past the faces o 65 of the secondary stitch-cams, the long-butt

meanwhile moving idly in the upper path t^1 . The advantages derived by the employment of my improved stitch-cams x^1 are that when the cam-block D^1 is positioned so as to cause the long-butt needles to be engaged 70 by the cams x^1 to knit the secondary thread into semi-courses of stitches, in co-operation with the knitting of the other thread by the short-butt needles and the cams of the main cam-block, in producing the split-foot 75 portion of the stocking, the block D^1 is located much nearer the cylinder than heretofore thereby providing correspondingly increased cam surface for supporting the long-butt needles when they are in knitting 80 action. As thus devised, the wear upon the long-butt needles is materially reduced, whereas, formerly the relation of the block D^1 to the cylinder when producing split-foot 85 knitting was necessarily such that the distance between the normal vertical inner face, as o , of the stitch-cams and the face of the cylinder exceeded the length of the butts of the short-butt needles, and the long-butts were necessarily materially longer than with 90 the present arrangement.

The immediately following description relates to the construction, arrangement and manner of operation of the means represented for controlling the movements of the 95 secondary cam-block D^1 : To an intermittently actuated cam-shaft s^1 is fixed a barrel-cam or drum f having a narrow sectional cam-like raised rib B secured to its periphery. Co-operating therewith is a light pivotally mounted lever f^1 having its front or free end disposed in the path of and arranged to frictionally engage said rib, and having its opposite or rear end jointed to a vertically extending link f^2 , in turn jointed to the bent 100 horizontal member of the bell-crank lever f^3 pivoted at f^4 to an ear of the table a^2 . The other arm of lever f^3 is attached to a link f^5 , jointed to a bent lever h pivoted at 105 h^1 to the cam-plate H ; the other end of lever h being joint-connected to the base of the secondary cam-block D^1 . Thus it is obvious that the swinging levers f^1 , etc., are adapted to impart a lateral sliding movement to the cam-block D^1 , the construction and arrangement of the parts being such that when the free end of the lever f^1 engages the periphery of the drum f itself, the block will thereby be moved to the inward position, close to the cylinder, as in 110 normal double-feed knitting, but when in engagement with the highest portions b and b^1 of the rib B , as in producing the heel and toe pockets, respectively, the block will be moved to the maximum outer position, the inactive or long-butt needles then oscillating 115 idly past the secondary cams. In producing the split-foot portion of the stocking, the main cam-block D is in position so as to be engaged by the short-butt needles to knit 120

the corresponding thread into semi-circular courses of stitches. At the same time, the other thread is also being knitted into semi-courses and joined to the first-named semi-courses by the operative engagement of the long-butt needles with the cams of the secondary cam-block, the latter then being in the mid-position with relation to the cylinder, as before stated. Figs. 1, 2 and 3 represent the corresponding position of the other coöperating elements. Figs. 2 and 3 show most clearly the then working relation of the lever f^1 to the intermediate cam-section c . In this mid-position of the secondary cam-block the butts of the short-butt needles reciprocate in the lower plane t (Fig. 4). As thus temporarily positioned, the outer ends of the butts of the short-butt needles will clear the bottom or back end of the lateral recesses n^2 of the two stitch-cams x^1 . At the same time, too, the construction is such that upon deflecting the long-butt needles downward from the inactive plane t^1 to the working plane t , the butts are adapted to slide upwardly on the inclined surface n^1 of the cam x^1 (bridging the recess n^2) past the point e and contact with the adjacent beveled side of the upper needle-guide m^1 , the resulting action upon the long-butt needles being substantially the same as in normal knitting.

The maximum lateral width of the inclined butt-engaging surface n^1 is slightly more than the length of the butts of the long-butt needles, or rather, the length of the portion of the butts projecting from the outer face of the needle-cylinder when the cams are in the inward position, and having the lateral depth of the recessed or cut-away portion n^2 somewhat less than the length of the butt portion of the short-butt needles extending outward from the cylinder's face. Thus, it will be apparent that provision is made for the coöperative engagement of the butts of all the needles with the stitch-cams x^1 when the cam-block D^1 is positioned inward, as in plain double-feed knitting, but when the said cam-block is in the outward position, as in producing the heel and toe pockets, none of the butts can engage the cams, whereas in knitting the split-foot portion of the stocking, the last-named cam-block then being in the mid position, the butts of the long-butt needles will operatively engage the cams x^1 .

The machine may be readily converted into one adapted to produce plain knitted stockings by simply disconnecting or rendering inoperative the secondary cam-block, thus moving its stitch-cams out of knitting action.

I claim as my invention:—

1. In a knitting-machine adapted to produce a split-foot stocking, the combination with the needle-carrying cylinder, of a pair of cam-blocks, a pair of oppositely disposed

stitch cams secured to the inner end portion of each of said cam-blocks, and means for automatically moving one of said cam-blocks radially toward and from the face of the cylinder at predetermined points during the knitting of the stocking, the upper portion of the normal inner vertical faces of the stitch-cams of the said movable cam-block being cut away or laterally recessed a limited extent, to form thereacross an unobstructed passage for the butts of certain needles.

2. In a circular stocking-knitting machine provided with a revoluble needle-cylinder carrying needles having butts varying in length, the combination therewith of substantially diametrically opposed main and secondary cam-blocks arranged with relation to the cylinder, a pair of oppositely disposed stitch-cams fixed to the inner end of the secondary cam-block, the vertical inner faces of the said stitch-cams being recessed thereacross to form a passage for the butts of the short-butt needles, means for moving the last-named cam-block whereby the short-butt needles are adapted to reciprocate idly past in the recessed portion of the stitch-cams, as when the split-foot part of a stocking is being produced, said stitch-cams at substantially the same time adapted to be in normal working engagement with the butts of the other needles, substantially as hereinbefore described.

3. A knitting machine having in combination a needle-cylinder, a main cam-block, a secondary cam-block movable with relation to said needle-cylinder, stitch-cams fixed to the last named cam-block, said stitch-cams being recessed on their inner faces to receive the butts of certain needles, a cam-shaft, and means for operating the secondary cam-block from said cam-shaft.

4. A knitting machine having in combination a needle-cylinder, main and secondary cam-blocks, a pair of oppositely disposed stitch-cams fixed to said secondary cam-block, each of said stitch-cams being provided with a lateral recess in its inner face to receive the butts of certain needles, a cam-shaft, and means operated from said cam-shaft for moving the said secondary cam-block radially with relation to the needle-cylinder.

5. A cam-block capable of being mounted for endwise movement in a stocking-knitting machine, a pair of oppositely inclined stitch-cams secured to the inner end of the cam-block, and having the upper portion of each of said stitch-cams provided with a lateral notch or recess in alinement with each other, and when the cam-block is normally mounted in the machine, having said recessed portions in horizontal alinement with and forming a continuation of the lower track or guiding path for the butts of the working needles.

6. In a rotary stocking-knitting machine having a needle-carrying cylinder, a main cam-block, a secondary cam-block, a pair of oppositely disposed stitch-cams fixed to the inner end portion of said secondary cam-block, said stitch-cams having a portion of their inner faces recessed to provide a path for the free passage of certain temporarily inactive needles, said path also being in 10 horizontal alinement with the normal knitting plane, and means for moving said secondary cam-block radially with relation to the cylinder.

7. In a knitting machine, the combination, with a series of long butt needles and 15 a series of short butt needles, of main stitch cams and secondary stitch cams, each of said secondary stitch cams being provided with a recess through which the short butt 20 needles may pass without being actuated

when said secondary stitch cams are in position to engage the long butt needles.

8. In a knitting machine, the combination, with a series of long butt needles and a series of short butt needles, of main stitch 25 cams and secondary stitch cams, each of said secondary stitch-cams being provided with a recess through which the short butt needles may pass without being actuated when said secondary stitch cams are in position to engage the long butt needles, and means for moving said secondary stitch cams 30 radially.

In testimony whereof I have affixed my signature in presence of two witnesses.

JOHN LAWSON.
